GARMENT SUPPORTER

Michael Hawie, Greens Farms, Conn., assignor to
The Hawie Manufacturing Co., Bridgeport,
Conn.

Application November 27, 1935, Serial No. 51,891

6 Claims. (Cl. 24—245)

This invention relates to improvements in garment supports and more especially to novel means for connecting a button tab to a loop member.

Usually button tabs have been connected to the loop member by means which bites into or requires perforation of the tab and this results in weakening the tab so that it has a short life. In accordance with the present invention the tab instead of being weakened is left imperforate and provided with a reinforced shoulder which is clamped to the loop by special fastening means.

It will therefore be understood that the primary purpose of the present invention is to provide connecting means for joining the tab and loop, the connecting means being of such character that the joint will be stronger and more positive than those heretofore employed, and the connection may be made rapidly.

With the foregoing objects outlined and with other objects in view which will appear as the description proceeds, the invention consists in the novel features hereinafter disclosed in detail, illustrated in the accompanying drawing and more particularly pointed out in the appended claims.

In the drawing:

Fig. 1 is a front elevation of my improved structure.

Fig. 2 is a vertical sectional view of the same taken on the line 2—2 of Fig. 1.

Fig. 3 is an elevation taken from the rear of the loop member and showing the tab in extended position before it is folded down to place the button of the tab in position to engage the loop.

Fig. 4 is an elevation of the tab detached from the loop member.

Fig. 5 is an edge view of the same.

Fig. 6 is a perspective view of the fastener element of the structure with the tongues of such element extended.

Fig. 7 is a similar view with the tongues bent toward one another to illustrate the position of the tongues when the fastener is in place in the structure.

Fig. 8 is a sectional view of the fastener taken on the line 8—8 of Fig. 6.

Referring to the drawing, 9 is a conventional loop member preferably formed of rigid metal and having an upper bar portion 10, an intermediate button-receiving portion 11 and a lower button-retaining portion 12.

A conventional metal eye 13 to be secured to the garment supporter (not shown), has a lower bar 14 that is joined to the bar 10 of the loop

15 also preferably made of metal. The member 15 provides an abutment surface at the upper end of the loop for a purpose hereinafter explained.

A button-tab member 16 is associated with the metal parts and preferably consists of a strip 17 of textile tape provided at its upper end with an enlarged transverse shoulder 18 and at its lower end with a button 19. The parts 18 and 19 are preferably formed of relatively stiff rubber and the part 18 is preferably triangular in cross section as best shown in Fig. 5, in order to provide an elongated abutment surface 20 which extends across the tape. The parts 18 and 19 may be secured to the tape 17 by vulcanization, adhesives or the like, but it will be noted that the parts 18 and 19 are imperforate and the tape 17 is also imperforate to eliminate weakening of the button tab.

A fastening member 21 is adapted to span a portion of the loop, and is employed in securing the tab to the loop. Such fastening member is best shown in Figs. 6 to 8 inclusive. It will be noted that it consists of an arc-shaped strip of metal having its medial portion 22 stamped into channel shape cross-section, as shown at 23 in Fig. 25 8, but the ends of the fastening member are left flat to provide tongues 24 which when bent toward one another may be used to secure downwardly converging portions 25 of the loop to the shoulder 18 of the tab, while the abutment surface 20 of the 30 latter is in engagement with the hinge element 15. In other words, in assembling the parts, the abutment surface 20 may be placed in abutting relation with the lower end of the hinge member 15 and then when the fastening member 21 is placed 35 in position and the tongues 24 are bent backward upon the shoulder 18, they will clamp the shoulder to the converging portions 25 of the loop and from that time on, will hold the abutment surface 20 in engagement with the member 15, whereby, 40 as the tab is placed in the position shown in Figs. 1 and 2, the shoulder and hinge member will cooperate with the fastening member to prevent detachment of the button tab from the loop.

As the member 21 is of arc shape, its highest 45 portion is brought in close proximity to the hinge element 15 to prevent the shoulder 18 from working loose. Furthermore, the arc formation enables the tongues 24 to be bent back toward the medial portion of the part 21 in fastening this 50 part to the loop member, and consequently the tongues can effectively grip both end portions of the shoulder 18.

From the above it is believed that my improved structure and method of assembling the parts 55

may be readily understood and it is obvious that changes may be made in the details disclosed without departing from the spirit of the invention as expressed in the claims.

5. What is claimed and desired to be secured by Letters Patent is:

1. A garment fastener comprising a loop member and a tab member, said loop member being provided at its upper end with an abutment surface, a button-tab member folded over the upper end portion of the loop member and having a transversely extending shoulder at its upper end provided with an abutment surface engaging the abutment surface at the upper end of the loop, 10 and a fastening member spanning the loop and having tongue portions for clamping said shoulder.

2. A garment fastener comprising a loop member and a tab member, said loop member being provided at its upper end with an abutment surface, a button-tab member folded over the upper end portion of the loop member and having a transversely extending shoulder at its upper end provided with an abutment surface engaging the abutment surface at the upper end of the loop, 15 and a separate arc-shaped fastening member spanning the loop and having tongue portions at its ends for clamping said shoulder against the loop.

3. A garment fastener comprising a loop member and a tab member, said loop member being provided at its upper end with an abutment surface, a button-tab member folded over the upper end portion of the loop member and having a transversely extending shoulder at its upper end provided with an abutment surface engaging the abutment surface at the upper end of the loop, 20 and a fastening member spanning the loop and having tongue portions for clamping said shoulder, the loop member having downwardly converging portions interlocked with said tongues.

4. A garment fastener comprising a loop member having an upper bar portion, an eye, a hinge member joining the eye to the bar portion of the loop member and forming an abutment surface extending transversely across the loop member, a 5 button-tab member folded over said hinge member and having an enlarged shoulder at its upper end and a button at its lower end, said shoulder engaging said abutment surface, and separate means for clamping the end portions of the 10 shoulder of the tab to the loop.

5. A garment fastener comprising a loop member having an upper bar portion, an eye, a hinge member joining the eye to the bar portion of the loop member and forming an abutment surface 15 extending transversely across the loop member, a button-tab member folded over said hinge member and having an enlarged shoulder at its upper end and a button at its lower end, said shoulder 20 engaging said abutment surface, and means for 25 clamping the shoulder portion of the tab to the loop, said means consisting of a metal strip spanning the upper end portion of the loop member and having tongues for clamping the shoulder portion of the tab member in position.

6. A garment fastener comprising a loop member having an upper bar portion and downwardly converging portions immediately below the bar portion, an eye at the upper end of the loop member, an abutment surface arranged at the upper 30 end of the loop member, a tab folded over said bar portion and extending through the eye, said tab having a transverse enlarged shoulder at its upper end abutting said abutment surface, a fastening member spanning the loop member and 35 having tongues at its ends engaging the converging portions of the loop member and clamping said shoulder to the loop member, and a button cooperating with the loop member and arranged at the lower end of the tab.

40 MICHAEL HAWIE.
